Primary Examiner — Cynthia Ramirez(74) *Attorney, Agent, or Firm* — Patent Procurement Services**CLAIM**

The ornamental design for a block pallet, as shown and described.

DESCRIPTION

FIG. 1 is a perspective top view of a block pallet showing my new design;

FIG. 2 is a top plan view thereof;

FIG. 3 is a side view, with the other side being identical thereof;

FIG. 4 is a front view, with the rear being identical thereof;

FIG. 5 is a perspective bottom view thereof; and,

FIG. 6 is a bottom plan view thereof.

The broken lines shown in FIGS. 5 and 6 are included for the purpose of illustrating environment and form no part of the claimed design.

1 Claim, 2 Drawing Sheets# US D647,685 S
